MARINE STEERING AND PROPELLING
DEVICE

Walter Leland Jones, Webster Groves, Mo.

Application August 18, 1947, Serial No. 769,190

3 Claims. (Cl. 115—29)

1

This invention relates to a marine steering and propelling device and more particularly to a portable steering and propelling device for water craft and the like.

Among the several objects of this invention may be noted the provision of a portable steering and propelling device operable in deep or shallow water which may be controlled to any of a wide range of steering positions, or at the operator's discretion may be conveniently and quickly set to either of two predetermined steering positions; the provision of a portable steering and propelling device which will serve to propel the boat to which it is attached; the provision of a device of the class described that when not in actual use for steering or propelling does not interfere with the desirable natural movements of the boat; the provision of a device of this class which will provide an additional keel effect; and the provision of a portable steering and propelling device which may be completely and conveniently controlled without interfering with the freedom of the operator's hands. Other objects will be in part apparent and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which is illustrated one of various possible embodiments of the invention.

Fig. 1 is a side elevation of the portable steering and propelling device of the present invention attached to a canoe, with parts broken away;

Fig. 2 is a top plan view of the portable steering and propelling device and the canoe of Fig. 1 with parts broken away;

Fig. 3 is a side elevation of the portable steering and propelling device of Fig. 1 on an enlarged scale illustrating a hinging action;

Fig. 4 is a top plan view of Fig. 3 illustrating various rudder positions;

Fig. 5 is a side view on an enlarged scale of the foot pedal of Fig. 1;

Fig. 6 is a top view on an enlarged scale of the foot pedals of Fig. 2;

Fig. 7 is a front view of the foot pedal of Fig. 5 as viewed from line 1—1 of Fig. 5; and,

Fig. 8 is a cross section taken substantially along the line 8—8 of Fig. 3.

Similar reference characters indicate corresponding parts throughout the several views of the drawings.

2

The use of one particular boat in all types of water such as swift-flowing streams, sluggish rivers or still lakes is difficult because a keel construction that is advantageous in one type of water will be detrimental in another. Thus, where rapid maneuverability is desired or passage through swift water is anticipated a large keel is not advantageous, while in slow water a small keel will cause undue drifting. Although it is possible to have an assortment of several keels adapted to be detachably fastened to the bottom of any particular boat to render such boat operable in the particular type of water desired, this is both expensive and time consuming.

15 In accordance with the present invention a keel effect of the desired degree is at the instantaneous control of the operator and moreover delicate control of the boat's direction is available. Furthermore, more completely to enable the operator to control his craft, propulsion by means of the same device is provided, so that relative movement between the boat and the water may be supplied at all times.

The novel device of the present invention provides in addition to the desirable keel features, above mentioned, a portable and quickly attachable steering and propelling device which when not energized by the operator interferes in no way with the natural floating characteristics of the craft to which it is attached. In other words, even when this device is affixed to the craft it interferes in no way with normal operation, and the boat handles as if the device were not so affixed. However, at the desire of the operator 30 additional keel effect, rudder action in either of two predetermined positions, or rudder action intermediate either of two predetermined positions or propulsion of the craft may be conveniently accomplished.

35 Referring now more particularly to the drawings, a water craft, such as a canoe, is indicated generally at numeral 1. The portable steering and propeller device of the present invention is indicated generally by numeral 3. A quick-detachable stern clamp 5 is removably affixed to the stern of boat 1 by means of a bolt 7. The forward end of the clamp 5 is formed so as to fit the contours of the boat 1 and resilient thongs 9 are provided for such mounting. Stern clamp 5 is provided with a mooring eye 10. A rudder block 11 is pivotally mounted by means of a bolt 13 to the stern clamp 5. Stern clamp 5 and rudder block 11 comprise a rudder support. The sides of block 11 extend forward to provide a bearing for bolt 13 and side support for block 11. The rear portion of the rudder block

40

45

50

55

11 carries a bearing bracket 15. A rudder post 17 is supported by and extends through the bearing bracket 15. The rudder post 17 carries a rudder and propeller assembly 19 comprising a rigid plate 21 and a flexible fish tail part 23. The assembly 19 is adjustably mounted on the lower end of the rudder post 17 by any suitable means permitting the rudder to be selectively positioned at any one of a number of different depths. As illustrated, assembly 19 is vertically bored to receive the lower end of rudder post 17. Assembly 19 may be maintained at a desired depth by means of a pin 25 extending through a transverse aperture of assembly 19 and through any one of a number of transverse apertures 27 of rudder post 17. This adjustment is illustrated by the two different positions of assembly 19 shown in Figs. 1 and 3. A disc 29 which carries an eccentrically mounted crank pin 31 is rigidly affixed to the rudder post 17 by means of a pin 33. The disc 29 and the eccentric pin 31 takes the place of the usual tiller bar. The assembly 19 is so affixed to the rudder post 17 and is of such fore and aft length and its distance from clamp 5 is such as to allow free 360° rotation of the rudder 19 without fouling the boat.

A port control cable 35 and a starboard control cable 37, each cable being provided with a loop or eye at its extremity, is coupled to the crank pin 31. A cable guide 39 and a cable guide 41 securely mounted on the sides of block 11 are provided to guide cables 35 and 37, respectively. The forward looped extremities or eyes of cables 35 and 37 pass through apertures 43 and 45, respectively, and are coupled to control members pedals 47 and 49 by means of pins 51 and 53. The pedals 47 and 49 are pivotally suspended by means of hinges 55 and 57 from supports 59 and 61. These supports are adjustably and quick-detachably mounted on the inner and under side of the gunwales of boat 1 by means of bolts 63 and 65 and clamps 67 and 69. The lengths of the cables 35 and 37 and the distance of the pedals from the crank constituted by disc 29 and crank pin 31 are made such that when both pedals are maintained in a neutral position, intermediate their limits of swinging movement, corresponding to the neutral position of the rudder (as illustrated in Figs. 1 and 2) the cables are maintained taut to hold the rudder in its neutral position. As shown in Figs. 1 and 2, in this neutral position the pedals extend substantially vertically downward from their hinge pivots. If the boatman uses his feet to apply equal forces to the two pedals tending to swing them forward from their neutral position of Figs. 1 and 2, the cables 35 and 37 will be maintained taut and the rudder will be positively held in neutral position. If he releases his feet, the pedals are freed for swinging movement toward and away from the stern of the boat. It is essential that the ends of the cables attached to the pedals be capable of moving through a distance at least slightly greater than the throw of the crank pin 31 (i. e., a distance slightly greater than the diameter of the circle of movement of the pin). This is accomplished by spacing the points of attachment of the cables 35 and 37 to the pedals at 43 and 45 from the pivots of the pedals a distance greater than the throw of the crank pin 31, so that the throw of each pedal is greater than that of the crank (the throw of the pedals being measured from the hinges 55 and 57 to the apertures 43 and 45).

Operation is as follows:

The aft portion of the device 3 is attached to the stern of the boat 1 by means of the bolt 1 and the pedal assemblies are attached to the opposite gunwales at a convenient distance from the operator and at the proper distance from the stern by means of bolts 63 and 65 and clamps 67 and 69. One end of cable 35 is inserted through aperture 43 and looped over pin 51, while the other end is passed through cable guide 39 and looped over crank pin 31. The ends of cable 37 are similarly looped over pin 53 and crank pin 31, respectively, so that the cable 67 passes through cable guide 41 and aperture 45. Assembly 19 is then adjusted to a desired depth by inserting pin 25 to any one of the holes 27.

The boat 1 while floating free will not be affected in any manner by the operation of the device 3 if the pedals 47 and 49 are undisturbed.

If there is relative motion between the water and the boat, assembly 19 is free to swing continuously and thus streamline itself with the water current provided, of course, that the boatman leaves the pedals free. Considering the action under these circumstances, as the rudder swings counterclockwise from its neutral position D illustrated in Fig. 2, it will be seen that during the initial phase of the rotation of the rudder, the crank pin 31 will pull on cable 37 and swing back the pedal 49, and cable 35 will simply slack off. This action occurs until the rudder and the crank pin reach the position B shown in Fig. 4. Then, the pin pulls both cables back until the reach of the cable 37 between the pin 31 and the guide 41 passes over the axis of the post 17. Then cable 37 slacks off and pedal 49 swings forward. Meanwhile pedal 47 is being swung back by cable 35. This continues until the reach of the cable 35 between the pin 31 and the guide 39 passes over the axis of the post 17, and then cable 35 slacks off and pedal 47 swings forward. At the conclusion of rotation of pin 31 through a full arc, back to position D of Fig. 4, both pedals are back in their neutral position. This action is permitted by reason of having the distances from the pivots of the pedals to the points of attachment of the cables to the pedals greater than the throw of the crank, and by having the pedals linked together for movement only through the cable connections to the crank pin 31. Thus, if the forward water motion is greater than that of the boat 1, the normal trailing edge 23 will align itself with the current so as to be forward of the shaft 17, such as is illustrated in an intermediate position by position A of Fig. 4.

If it is desired to direct the boat 1 to starboard, pedal 47 is pushed forward to its extreme limit and pedal 49 is not actuated. This action causes cable 35 to be tensioned and crank pin 31 to be held in the position illustrated in Fig. 4. This is because the line of pull of the cable where applied to the crank pin 31 is directed through the crank center, which is to say through the center of shaft 17. As long as forward pressure is applied to pedal 47, assembly 19 will be held in the position B of Fig. 4. By pressure on only the pedal 49 the assembly 19 may be caused to assume the alternate predetermined position C, shown in Fig. 4. These two positions are determined by the diameter of the plate 29, the position of the crank pin 21 thereon, and the relative positions of the cable guides 39 and 49. Rudder assembly 19 may be positioned to any desired intermediate steering

position between positions B and C by cooperative pressure on pedals 47 and 49 by the operator. The relative pressure applied to each pedal will determine the actual intermediate position of assembly 19.

To provide for additional keel effect the operator actuates the pedals so that the pressure on pedal 47 is equal to that on pedal 49. In response to this action assembly 19 will align itself in its neutral plane, position D of Fig. 4. The amount of keel effect may be conveniently decreased or increased by raising or lowering assembly 19 on shaft 17.

As it is desirable to have relative motion between the boat 1 and the water to cause the craft to respond to rudder actuation the resilient portion 23 of assembly 19 has been provided. By alternate pushing of pedals 47 and 49, assembly 19 will be caused to move rapidly between the positions B and C and the resultant "fish-tail" action will propel the boat 31 forward. Once such relative movement is imparted to the boat, rudder action may be used to control the boat's heading.

The flexible fish-tail section 23 of rudder 19 is constructed of a resilient, semi-rigid material, such as stiff rubber, so that it may be conveniently trimmed, as illustrated, to fit the contours of the boat to which the rudder device is attached so that it will clear the boat during complete rotations of the rudder assembly 19.

The hinging action between block 9 and support 11 provides protection for the rudder device of the present invention. An obstruction passing under the boat will cause the assembly 19 and its associated components to rotate upwardly on the axis of bolt 13 rather than causing damage. A shear pin 71 may also be provided to prevent light water-borne objects from causing the assembly 19 to be lifted from the water by the aforementioned hinging action. This hinging action also enables the entire assembly to be more conveniently folded together for carrying when not mounted on the boat.

As both pedals 47 and 49 and the aft portion of the novel rudder and propeller device 3 of the present invention are quickly detachable by means of only three bolts 7, 63 and 65 and the control cables 35 and 37 are quickly removable merely by unlooping from the pins 51 and 53 and crank pin 31, rapid mounting and dismantling is conveniently accomplished.

Although the aft portion of device 3 is mounted on boat 1 by means of the stern clamp 9 and bolt 7, any other means of attachment may be used. For example, the aft portion of rudder device 3 may be affixed to the transom of a row-boat by means of a block and bracket assembly.

The cable guides 39 and 41 may be conveniently replaced by appropriate pulley assemblies, and if such operation is desired, cables 35 and 37 may be crossed so as to provide a port heading when pedal 47 is pushed, and a starboard heading when pedal 49 is pushed.

It is also to be understood that although pedals 47 and 49 are mounted for foot operation, the aft portion of device 3 may be operated manually.

In view of the above, it will be seen that the several objects of the invention are achieved and other advantageous results attained.

As many changes could be made in the above constructions without departing from the scope of the invention, it is intended that all matter contained in the above description or shown in

the accompanying drawings shall be interpreted as illustrative and not in a limiting sense.

I claim:

1. Rudder mechanism for a boat comprising a rudder support at the stern of the boat, a rudder post rotary in the support, a rudder on the post adapted for free rotation through a full circle, a crank at the upper end of the post, pedals pivoted at opposite sides of the boat for swinging movement toward and away from the stern of the boat, cable connections from the pedals to the crank, the length of the cable connections and the distance of the pedals from the crank being such that when both pedals are maintained in a neutral position intermediate the limits of their swinging movement corresponding to the neutral position of the rudder, the cable connections are maintained taut to hold the rudder in neutral position, the cable connections being attached to the pedals at points spaced from the pivots of the pedals a distance greater than the throw of the crank, whereby, when both pedals are free, the rudder may swing freely through a full circle in either direction, and whereby the pedals may be positively actuated to hold the rudder in neutral position or positively swing it to one side or the other.
2. Rudder mechanism for a boat comprising a rudder support at the stern of the boat, a rudder post rotary in the support, a rudder on the post adapted for free rotation through a full circle, a crank at the upper end of the post, pedals pivoted at opposite sides of the boat for swinging movement about a horizontal axis transverse to the boat and toward and away from the stern of the boat, the pedals hanging down from their pivots, cable connections from the pedals to the crank, the length of the cable connections and the distance of the pedals from the crank being such that when both pedals are maintained in a neutral position intermediate the limits of their swinging movement corresponding to the neutral position of the rudder, the cable connections are maintained taut to hold the rudder in neutral position, the cable connections being attached to the pedals at points spaced from the pivots of the pedals a distance greater than the throw of the crank, whereby, when both pedals are free, the rudder may swing freely through a full circle in either direction, and whereby the pedals may be positively actuated to hold the rudder in neutral position or positively swing it to one side or the other.
3. Rudder mechanism for a boat comprising a rudder support at the stern of the boat, a rudder post rotary in the support, a rudder on the post adapted for free rotation through a full circle, a crank at the upper end of the post having an upwardly extending crank pin, pedals pivoted at opposite sides of the boat for swinging movement about a horizontal axis transverse to the boat and toward and away from the stern of the boat, the pedals hanging down from their pivots, cable connections from the pedals to the crank pin, the length of the cable connections and the distance of the pedals from the crank pin being such that when both pedals are maintained in a neutral position intermediate the limits of their swinging movement corresponding to the neutral position of the rudder, the cable connections are maintained taut to hold the rudder in neutral position, the cable connections being attached to the pedals at

points spaced from the pivots of the pedals a distance greater than the throw of the crank pin, whereby, when both pedals are free, the rudder may swing freely through a full circle in either direction, and whereby maximum forward actuation of either pedal alone will hold the rudder in either of two limiting steering positions.
